RANGE APPARATUS

Paul M. Weyrick, Ashland, Ohio, assignor to
Westinghouse Electric Corporation, East Pittsburgh, Pa., a corporation of Pennsylvania

Application September 19, 1950, Serial No. 185,609

6 Claims. (Cl. 219—37)

1

This invention relates to a deep well cooker for an electric range and more particularly to a deep well cooker in which the heating unit may be elevated to serve as a surface heating unit.

It is an object of the invention to provide a two-level cooking unit which may be elevated to a surface heating position and positively locked in such position.

It is another object of the invention to provide a two-level cooking unit which has a reduced number of parts, is relatively inexpensive to manufacture and is easy to operate.

It is still another object to provide a two-level cooking unit having smooth inner surfaces, thereby facilitating maintenance of cleanliness in the unit.

These and other objects are effected by my invention as will be apparent from the following description and claims taken in connection with the accompanying drawings, forming a part of this application, in which:

Fig. 1 is a side elevation of a two-level cooking unit constructed in accordance with my invention, the heating unit being shown in its lower position;

Fig. 2 is a cross-section taken on line II—II of Fig. 1, the left hand portion being taken at a lower level than the right hand portion;

Fig. 3 is a perspective view of the two-level cooker with the heating unit in an intermediate position, portions being cut away for clarity; and

Fig. 4 is a side elevation similar to Fig. 1, but with the heating unit locked in its upper position.

Referring to the drawings, especially Figs. 1 and 2, there is shown a two-level cooking unit 10 disposed in a conventional range platform 14. The platform is provided with an opening defined by an annular depending flange 16, and the cooking unit 10 is provided with an annular support ring 18 disposed in the opening. The support ring 18 has a relatively narrow cylindrical band portion 20 and an outwardly extending annular flange 22 resting on the platform 14. The support ring is rigidly attached to the platform in any desirable manner, although for simplicity I have shown it attached to the platform flange 16 by rivets 24.

A pot-like casing 26, as best shown in Fig. 3, having a relatively deep cylindrical wall 28 and a bottom wall 30 is slidably received within the support ring 18. The upper edge of the wall 28 is bent outwardly to provide a peripheral flange 22 which normally overlies the flange 22 to there-

2

by support the casing. A plurality of vertically elongated slots 34 are provided in the wall 28 and are preferably equidistant to each other. A wide slot 36 having substantially the same height as slots 34 is also provided in the wall 28 and is preferably spaced equidistantly from the adjacent slots 34. The lower end of slot 36 extends into the bottom wall 30.

An electrical heating unit 38 is disposed within the casing 26. The heating unit may be provided with a heater 40 of the sheathed type, formed to provide a horizontal heating surface portion. It is provided with a plurality of terminal portions 42 which extend outwardly through the slot 36 to a common terminal block 44 wherein connections to a power supply may be made. The sheathed heater is circular in plan and is adapted to support a cooking vessel 46, as shown in dot-and-dash lines in Fig. 1. The sheathed heater 40 is supported by a plurality of radial members 48 which are equally spaced from each other and have extended support arms 50 which extend outwardly through the slots 34. The arms 50 are supported at the lower edges of the slots 34 when the heating unit is in the lower position. The heating unit 38 is jointly rotatable with the casing 26 but is movable vertically with respect to the same. Adjacent the lower edge of each slot 34, a horizontal pad 52 is provided by embossing upwardly a small portion of the bottom wall 30. A large bearing surface is thus provided which enables the heating unit 38 to be amply supported when the casing 26 is made of soft light-gauge material such as aluminum.

35 The support ring 18 has a plurality of vertically extending notches 54 which are in registry with the slots 34 when the heating unit is in the lower position as shown in Figs. 1 and 2. The lower end of each notch 54 is open and is preferably divergent while the upper end of each notch 40 communicates with a laterally extending slot or horizontal ledge portion 56.

The casing 26 is keyed to the support ring 18 to prevent angular movement of the casing relative to the ring, except under conditions which will subsequently be described, while being freely slideable therein in vertical direction. The keying structure includes two V-shaped notches 58 and 60, respectively, formed in the support ring 18 in adjoining relation, and a vertically extending rib 62 formed in the casing 26. The distance between the centers of the notches is substantially equal to the length of the slots 34. The rib 59 is provided by outwardly embossing a portion 55 of the casing and has a cross-sectional shape

similar to that of the notches 58 and 60 to permit slidable engagement therewith. The rib is somewhat shorter in length than the slots 34 but is upwardly displaced therefrom and is preferably extended up to the flange 32 for a purpose which will be explained later.

To facilitate vertical movement of the casing, a pair of diametrically opposed handles 66 are hingeably mounted on the flange 32.

The annular flange 16 may also be provided with two notches equal in size and spacing to the notches 58 and 60 to permit proper seating of the support ring 18 in the platform opening, but obviously they are not essential, since the platform opening may be made larger than shown. Also, the band 28 of the support ring 18 has a cut-away portion 62 substantially wider than the slot 36 and substantially in registry therewith.

To elevate the heating unit to its upper or surface cooking position, the vessel 46 is first lifted from the casing 26. The handles 66 are then grasped and the casing is lifted vertically to its upper limit of travel as shown in Fig. 3. Since the heating unit is supported within the casing by the support arms 50, the heating unit will be carried to its upper position when the casing is raised. The support arms 50 of the heating unit will be received by the notches 54 and their subsequent abutment against the upper end of the notches determines the upper limit of travel of the heating unit and the casing and prevents disengagement of the casing from the support ring 18. The rib 64 is thereby lifted out of engagement with the notch 58, unlocking the casing and permitting rotation of the casing in clockwise direction only (as viewed in Fig. 2). The casing is then rotated in clockwise direction, carrying the heater with it, until the support arms 50 abut the ends of the slots 56 and terminate further rotation. The lower edge of each of the slots 56 may be bent outwardly to provide pads 68 which provide large bearing surfaces for the support arms 50. At the end of such rotational movement the rib 64 is aligned with the notch 60. The casing may now be lowered to its lower level shown in Fig. 4, leaving the heating unit in the upper position where it is supported by support ring 18. The rib is now in engagement with notch 60 which also locks the casing against rotation in the same manner as notch 58.

To lower the heating unit to the lower or deep well cooking position the above sequence of operations is reversed.

The slot 36 serves as a clearance opening for the heater terminals 42 and the terminal block 44, and permits the heating unit to be moved vertically with respect to the casing; while the cut-away portion 62 serves as a clearance opening for the terminals and terminal block and permits the heating unit to be rotated horizontally as well as to be moved to the upper position.

The casing may be provided with an opening 18 in its bottom wall 28 to permit spillage of food to drain from the cooking unit. The inner surface of the casing wall 28 may be cleaned easily when the heating unit is in the lower position, since the support ring is disposed exteriorly of the casing and presents no interfering surfaces or sharp edges which would otherwise catch a cloth or abrade the fingers of the user. The inner surface of the bottom wall also may be rendered accessible for cleaning by grasping one of the support arms 50 and tilting the heat-

ing unit about the other two support arms as pivots.

When the heating unit is in its upper or surface cooking position, it cannot under any circumstances be dislodged from the supporting pads 68 except by lifting the casing 26 to its full limit, as shown in Fig. 3, and disengaging the rib 64 from the notch 60; since, as previously mentioned, the heating unit is not rotatable relative to the casing and the casing may only be rotated when the rib 64 is disengaged from its mating notches 58 and 60.

It will thus be seen that I have provided a two-level cooking unit that has relatively few components, is inexpensive to manufacture, is easy to operate and is reliable in performance.

While I have shown my invention in but one form, it will be obvious to those skilled in the art that it is not so limited, but is susceptible of various changes and modifications without departing from the spirit thereof.

What I claim is:

1. An adjustable level cooking unit comprising a support ring element, a cylindrical casing element movable within said support ring, an electrical heating unit horizontally disposed within said casing and adjustable to upper and lower positions, said casing having a plurality of vertically elongated slots and said heating unit having a plurality of arms extending through said slots whereby the rotative position of said heating element is controlled by said casing, said support ring having a plurality of horizontally disposed ledges for supporting said heater in the upper position and in a first rotative position, said heating unit being supported in the lower position by said casing and being movable between said upper and lower positions by said casing, said casing and said support ring having cooperating keying members including a locking member provided on one of said elements and a pair of spaced mating members provided on the other of said elements, said locking member being adapted to engage and be slidably confined by either of said mating members, said casing element being thereby locked against rotation but slidable in an axial direction, said locking member disengaging said mating members when the casing is in the upper position, thereby permitting rotation of said casing when in the upper position to move said heating unit into and out of engagement with said ledges, said locking member registering with one of said mating members when said heating unit is in said first rotative position in which it is in engagement with said ledges and registering with the other of said mating members when said heating unit is in a second rotative position out of engagement with said ledges.

2. The structure recited in claim 1 in which said locking member is a rib provided in said casing and said mating members are recessed portions provided in said support ring, said rib having a substantially greater vertical length than said recessed portions but having a substantially lesser vertical length than said casing.

3. The structure recited in claim 1 in which said support ring has a peripheral sheet metal wall and said ledges are provided by horizontally extending slots formed in said wall, each of said slots having one end opening downwardly and adapted to receive one of said arms.

4. An adjustable level cooking unit comprising a support ring element, a cylindrical sheet metal casing element rotatable and axially slidable

within said support ring, said support ring being substantially shorter in axial direction than said casing, an electrical heating unit horizontally disposed within said casing and adjustable to upper and lower positions by said casing, said casing having a plurality of vertically elongated slots and said heating unit having a plurality of arms extending outwardly through said slots, said heating unit being supported in the lower position by said casing and being jointly rotatable therewith, said support ring having a plurality of horizontally disposed ledges, and said heating unit being elevatable to said upper position by said casing, said casing being rotatable when elevated to effect engagement of said arms with said ledges, said ledges thereby supporting said heating unit in said upper position, said support ring having a vertically disposed passage adjacent each of said ledges and in communication therewith for guiding said arms into engagement with said ledges, and means for locking said casing against rotation but permitting vertical movement when said casing and said heating unit are in the lower position, said locking means being arranged to guide said arms into registry with said passages and comprising a vertically elongated keying member on said casing and a substantially shorter mating keying member on said support ring.

5. An adjustable level cooking unit comprising a support ring, a cylindrical casing movable within said support ring, an electrical heating unit disposed horizontally within said casing and adjustable to upper and lower positions, said casing having a plurality of vertically elongated slots and said heating unit having a plurality of arms extending outwardly through said slots, whereby the rotative position of said heating unit is controlled by said casing, said support ring having a plurality of horizontally disposed ledges for supporting said arms in a first rotative position of the heating unit and said casing, a vertical passage displaced angularly from each of said ledges for permitting vertical movement of said

arms in a second rotative position of said heating unit and said casing, and a passage providing for horizontal movement of said arms between said vertical passages and said ledges, said heating unit being supported by said casing at the lower end thereof when said heating unit is in said second rotative position and adapted to be raised and lowered by said casing, said casing and said support ring having cooperating keying members for retaining said casing against rotation from said first and second rotative positions, said keying members including a locking member provided on one of said elements and a plurality of angularly spaced mating members provided on the other of said elements, the keying member or members on one of said elements being vertically elongated, said keying members being positioned to be disengaged to permit rotative movement of said casing when the latter is in its uppermost position, said mating members being positioned to be engaged by said locking member when said casing is in said first and second rotative positions, respectively, and serving, upon downward movement of said casing, to retain the casing against rotation but to permit vertical sliding thereof, whereby said heating unit is positively locked on said ledges when in the upper position.

6. The structure recited in claim 5 in which said locking member is disposed on said casing and said mating members are disposed on said ring.

PAUL M. WEYRICK.
